UNITED STATES PATENT OFFICE.

GEORGE A. JOHNSON, OF CHICAGO, ILLINOIS, ASSIGNOR TO W. H. MINER, OF CHICAGO, ILLINOIS.

PACKING FOR REFRIGERATOR-DOORS.

1,139,038.

Specification of Letters Patent. Patented May 11, 1915.

Application filed August 11, 1913. Serial No. 784,042.

To all whom it may concern:

Be it known that I, GEORGE A. JOHNSON, a citizen of the United States, residing at Chicago, in the county of Cook and State of Illinois, have invented a certain new and useful Improvement in Packing for Refrigerator-Doors, of which the following is a full, clear, concise, and exact description, reference being had to the accompanying drawings, forming a part of this specification.

My invention relates to packing for refrigerator doors.

The object of my invention is to provide a door packing of simple construction and efficient operation.

In the drawings forming a part of this specification Figure 1 is a cross section of the meeting edges of a hinged door, and the wall or door-frame surrounding the same, and showing the door in open position; Fig. 2 is a plan view of a portion of said wall, the covering thereof being partly broken away to show the groove therein; Fig. 3 is a cross section of the meeting edges of a door and the wall surrounding the same with the door illustrated in closed position.

Referring to the drawings 4 represents a door, the edge thereof only being shown in the drawings, 5 a hinge by means of which the said door is hinged to the door-frame or wall 6 surrounding the door. The said wall surrounding the door is provided with a groove 7 longitudinally extended therein, having a central longitudinally disposed bead 8 forming with the sides of the groove a recess 9 at either side of said bead. Secured to said bead, preferably by the screws 10, is a resilient or yielding backing strip 11, the same being preferably formed of a strip of spring material bowed at either edge 12, 12, the meeting edges 13, 13 of the material of which it is formed being overlapped, as illustrated at the numeral 14, and perforated at intervals, as illustrated at the numeral 15, to receive a screw 10, by means of which the over-lapping edges of the spring material are held together and secured to said bead. In the outer wall 16 of said backing strip there are provided at suitable intervals the apertures 17 through which the screws 10 may be passed in

mounting the backing strip within the groove 7. The bowed edges 12 of the backing strip form at the forward faces of said backing strip parallel bearing faces 18, 18 spaced apart and engaging the flexible material 19, which bridges the said groove 7. The flexible material 19 comprises preferably the matting 20 and the canvas 21 stretched over the same, the said yielding material being secured to the faces of the wall surrounding the door by means of the nails 22, 22 driven therein.

When the door is in open position, as illustrated in Fig. 1, the expanded backing strip presses against the yielding material, and on closing of the door when the inner edge 23 of the door engages the yielding material the same is compressed between the bearing faces 18 of the yielding backing strip and the edge 23 of the door, the resisting backing strip being meanwhile compressed, and the bowed ends thereof forced rearwardly into the depressions 9, 9 at either side of the bead 8 within the groove 7 in the wall surrounding the door.

I claim:

In a packing for doors of refrigerator cars and the like, the combination with a door and an adjacent member having meeting edges when the door is in closed position, one of said edges being provided with a longitudinally extending groove therein, of yieldable, flexible, facing material bridging said groove, and yielding means for pressing said material outwardly firmly against the adjacent edge, said means including a longitudinally extending spring strip secured in said groove, said spring strip having rounded, spaced edges yieldingly engaging said material along two spaced parallel lines, whereby when the door is in closed position, said material is pressed into engagement with the adjacent edge along said spaced lines and said material between said lines is kept in contact with the adjacent edge to thereby provide a wide surface contact between the meeting edges of the door and adjacent member.

GEORGE A. JOHNSON.
